United States Patent Office

Des. 184,819
Patented Apr. 7, 1959

184,819

DISPENSING TRAILER OR SIMILAR ARTICLE

Harry B. Kuster, Cambridge City, Ind., assignor to Con-
verto Manufacturing Co., Inc., Cambridge City, Ind.

Application December 1, 1958, Serial No. 53,597

Term of patent 14 years

(Cl. D14—3)

FIG-1

Des. 184,819

PAGE 2

Des. 184,819

PAGE 3

Fig. 1 is a rear perspective view of a dispensing trailer or similar article, showing my new design.

Fig. 2 is a side elevational view of the dispensing trailer or similar article.

Fig. 3 is a top plan view of the dispensing trailer or similar article.

Fig. 4 is a rear elevational view of the dispensing trailer or similar article.

Fig. 5 is a front elevational view of the dispensing trailer or similar article.

Fig. 6 is a side elevational view of the dispensing trailer or similar article, in a closed condition.

Fig. 7 is a rear elevational view of the dispensing trailer or similar article, in a closed condition.

Fig. 8 is a front elevational view of the dispensing trailer or similar article, in a closed condition.

The dominant features of the design reside in the portions shown in full lines.

I claim:

The ornamental design for a dispensing trailer or similar article, as shown and described.
